Primary Examiner — Ian Simmons

Assistant Examiner — Keith Frank

(74) Attorney, Agent, or Firm — Norton Rose Fulbright
US LLP(57) **CLAIM**

The ornamental design for a cosmetic bottle, as shown and described.

DESCRIPTION

FIG. 1 is a top perspective view of a cosmetic bottle showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate the portions of the cosmetic bottle that form no part of the claimed design.

1 Claim, 6 Drawing Sheets# US D776,544 S
